(57) **CLAIM**

I claim the ornamental design for a backpack pet carrier, as shown and described.

DESCRIPTION

FIG. 1 is a perspective view of the backpack pet carrier showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a perspective view of another embodiment of the backpack pet carrier;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.

Dashed lines represent claimed stitching. Other dashed lines representing the buckles (in FIGS. 1, 3-8, and 10-14) and the leash strap (in FIGS. 1, 2, 8, and 9) are for the purpose of illustrating portions of a backpack pet carrier and form no part of the claimed design.
